(57) **CLAIM**

The ornamental design for a hitch mountable enclosed cargo carrier, as shown and described.

DESCRIPTION

FIG. 1 is a rear perspective view of the hitch mountable enclosed cargo carrier showing our new design;

FIG. 2 is a top plan view thereof;

FIG. 3 is a top plan view thereof in a position with the support arm pivoted away from the hitch mount;

FIG. 4 is a top plan view thereof in a position with the support arm pivoted away from the hitch mount and with the cargo bin rotated on the support arm;

FIG. 5 is a bottom plan view thereof;

FIG. 6 is a front elevational view thereof;

FIG. 7 is a rear elevational view thereof;

FIG. 8 is a right side elevational view thereof; and,

FIG. 9 is a left side elevational view thereof.
